Primary Examiner—Catherine Tuttle

(74) Attorney, Agent, or Firm—Emelyn L. Hiland

(57) **CLAIM**

The ornamental design for a bottle, as shown and described.

DESCRIPTION

FIG. 1 is a front perspective view showing our new design for a bottle, the oblique line shading being indicative of a transparent or translucent surface;

FIG. 2 is a front elevational view thereof;

FIG. 3 is a rear elevational view thereof;

FIGS. 4 and 5 are side elevational views thereof;

FIG. 6 is a top plan view thereof; and

FIG. 7 is a bottom view thereof;

FIG. 8 is a front perspective view showing a second embodiment of our new design for a bottle, the stippling being indicative of a colored surface;

FIG. 9 is a front elevational view thereof;

FIG. 10 is a rear elevational view thereof;

FIGS. 11 and 12 are side elevational views thereof;

FIG. 13 is a top plan view thereof; and

FIG. 14 is a bottom view thereof;

FIG. 15 is a front perspective view showing a third embodiment of our new design for a bottle, wherein the surface is white and opaque;

FIG. 16 is a front elevational view thereof;

FIG. 17 is a rear elevational view thereof;

FIGS. 18 and 19 are side elevational views thereof;

FIG. 20 is a top plan view thereof; and,

The broken lines are included for the purpose of illustrating the upper end and bottom surface portions of the bottle that form no part of the claimed design.

FIG. 21 is a bottom view thereof.
